UNITED STATES PATENT OFFICE.

JOHN L. KIVLAN, OF BOSTON, MASSACHUSETTS.

EXTENSIBLE RACK.

1,271,326.

Specification of Letters Patent. Patented July 2, 1918.

Application filed September 13, 1917. Serial No. 191,195.

To all whom it may concern:

Be it known that I, JOHN L. KIVLAN, a citizen of the United States, residing at Boston, in the county of Suffolk and State 5 of Massachusetts, have invented a certain new and useful Improvement in Extensible Racks, of which the following is a specification, reference being had therein to the accompanying drawings.

10 The invention relates to a new and useful improvement in extensible racks. In putting up fruits, vegetables and other provisions in glass jars by the cold pack process, so called, it is common after the goods 15 have been packed cold in the jars and the covers put on, to boil the filled closed jars in water. In carrying out this process it is common to use metal wash boilers in which the jars are placed, the boiler being filled 20 with water sufficient to cover the jars. If the jars are placed directly on the bottom of the boiler, the heat is liable to crack the jars and moreover the water does not come in contact with the bottom of the jars. It is 25 therefore preferable to have the jars supported on a rack so as to raise them slightly above the bottom of the boiler. It is also desirable to have the rack removable from the boiler, so that thereby the jars may be 30 assembled on the rack outside of the boiler, and then lowered into the boiler, and also so that they may be readily removed from the boiler by lifting out the rack.

Different sized boilers are used, and in order 35 to avoid the necessity of providing a variety of sizes of racks to accommodate the different boilers, the object of the present invention is to provide an extensible rack which in its most compact form will fit 40 a relatively small sized boiler, and which may be extended to fit boilers of one or more sizes larger than the smaller sized boiler.

The invention will be fully understood from the following description when taken 45 in connection with the accompanying drawings, and the novel features thereof will be pointed out and clearly defined in the claims at the close of this specification.

In the drawings, Figure 1 is a side elevation of a rack embodying my invention and showing in dotted lines a boiler in which the rack is placed, the rack being shown empty of jars.

Fig. 2 is a plan view of the rack removed 50 from the boiler and in its unexpanded form.

Fig. 3 is a plan view showing the rack in its expanded form.

Fig. 4 is a section on line 4—4 of Fig. 2.

Referring now to the drawings, 1 is the frame of the rack which is preferably of 60 hollow ovoid form corresponding in peripheral contour to the usual contour of wash boilers. This frame is also preferably made of sheet metal, and in order to combine strength with lightness and to enable it 65 to stand up a suitable height above the bottom of the boiler, the rim of the frame is made hollow, being preferably in cross section somewhat like an inverted U as shown in Fig. 4, thus having a flat top face a, an 70 inner peripheral wall b, and an outer peripheral wall c, and having an open bottom. Extending lengthwise outside of the two sides of the frame are two tubes 2, 2, each of which is supported on the outer ends respectively of a series of wire slide rods 3, 3, said rods 3, 3, passing loosely through perforations in the inner and outer peripheral walls of the frame, just below the top wall a of the frame. Said wire rods are thus supported in said apertures as bearings and are 75 slidably therein so that the said tubes 2, 2, which are connected with the rods 3, 3, may be moved in and out with relation to the sides of the frame. These tubes 2, 2, preferably extend somewhat less than the full length of the frame, being stopped about at the point where the bend of the frame begins at the ends, the exact length being immaterial.

At the two ends of the frame there are provided two bowed spring wire rods or bars 4, 4, each of which is connected intermediate its ends with the outer ends of a plurality of wire slide rods 5, said wire rods 5 passing 80 loosely through apertures in the inner and outer peripheral walls b, c, of the frame at substantially the same level that the wire rods 3 pass through the frame. These rods are thus supported in bearings formed by the apertures in the frame and are longitudinally slidable therein and thus the bent wire rods 4 which are supported thereby may be moved in and out with relation to the ends of the frame. The ends of the wire 85 rods 4 are telescoped into the tubes 2, 2, so that as the said rods 4, 4, are moved in and out with relation to the ends of the frame, the ends of the said rods 4, 4, will move in and out a corresponding distance 90

within the said tubes 2, 2. The said end rods 4, 4, should be of sufficient length so that when they are in the outermost position in use they will not be completely withdrawn from engagement with the tubes. These end rods 4, 4 should preferably be of sufficient spring tension so that their ends will tend to spread outwardly away from each other. The friction will retain the parts 10 in their adjusted position. When the said end rods are pulled outward into the extended form so that their ends do not extend so far into the tubes, the tendency of the said end rods to spring outwardly will cause 15 the side rods 2, 2 and the slide rods 3 on which they are mounted to move outwardly away from the sides of the frame. Thus the rack will be extended both at the ends and at the sides. If the spring of the wire is 20 not sufficient to move the side rods out they may be moved out by hand. The inner walls of the boiler 8 in which the rack is placed will, of course, limit the outward expansion 25 of the rack.

26 The walls *a*, *b*, *c*, of the frame are preferably formed with apertures 6 to permit free circulation of water. Preferably the rack is provided with handles 9 attached to the two end rods 4, 4 by which the rack 30 may be lifted out of the boiler and by which it may be held to put it into the boiler. These handles are preferably hinged to the end rods 4, 4, instead of being rigidly connected thereto, although this is not essential. 35 Preferably a wire netting 7 is attached to the upper side of the frame and extends over the open space surrounded by the frame to form a seat for the jars. The wire slide rods 3 at the sides, and 5 at the ends, together with the extensible end rods and side rods are sufficiently close together so as to 40 form a seat for the jars outside of the body of the frame.

45 Preferably the handles 9 are each provided with a hook 71 which may be hooked over the top rim of the boiler 8, so that if desired the rack may be hung in a suspended position in the upper part of the boiler.

50 What I claim is:

1. An extensible rack comprising a middle body portion, two bowed substantially U-shaped wires, the middle portions of the bows forming end rim portions for the rack, the branches of each of said wires forming a partial side rim outside of said body portion, and guides adjacent the sides and slidably secured to said body portion through 55 which the branches of the said wires are slide- 60 able to permit movement of said wires toward and away from each other to vary the

length of the rack, the said branches being capable of lateral spreading movement away from said body portion, the spreading of the branches of said wires permitting lateral movement of the guides away from said body portion. 65

2. An extensible rack comprising a middle body portion, two bowed substantially U-shaped wires, the middle portions of the bows forming end rim portions for the rack, the branches of each of said wires forming a partial side rim outside of said body portion, and guides adjacent the sides and slidably secured to said body portion through 70 which the branches of the said wires are slide- 75 able to permit movement of said wires toward and away from each other to vary the length of the rack, the said branches being capable of lateral spreading movement away from said body portion, the spreading of the branches of said wires permitting lateral movement of the guides away from said body portion, the bows of said end members having slideable guide connections with said 80 body portion. 85

3. An extensible rack comprising a middle body portion, two wires each bowed substantially U-shaped, the bowed middle portions of the wires forming end rim portions for the rack, the branches of each of said wires forming a partial side rim outside of said body portion, and guides adjacent the sides and slidably secured to said body portion through 90 which the branches of said wires are slide- 95 able to permit movement of said bow portions of the wires toward and away from each other to vary the length of the rack, the branches of said wires spreading outwardly to increase the width as the wires are moved lengthwise with relation to each other to extend the length of the rack, the spreading of the branches permitting lateral movement of the guides. 100

4. An extensible rack comprising a middle body portion, two bowed substantially U-shaped wires, the middle portions of the bows forming end rim portions for the rack, the branches of each of said wires forming a partial side rim outside of said body portion, the said wires being slideable toward and away from each other to vary the length of the rack, the said branches being capable of a lateral spreading movement away from 110 said body portion, and guides for the said wires, said guides being movable with relation to the body of the rack to permit the longitudinal and the spreading movement 115 of the wires. 120

In testimony whereof I affix my signature.
JOHN L. KIVLAN.
